A. D. GRANT

SMOKING DEVICE

Filed March 17, 1925

INVENTOR

Alexander D. Grant

John A. Raismith

BY

ATTORNEY

UNITED STATES PATENT OFFICE.

ALEXANDER D. GRANT, OF SAN JOSE, CALIFORNIA.

SMOKING DEVICE.

Application filed March 17, 1925. Serial No. 16,182.

To all whom it may concern:

Be it known that I, ALEXANDER D. GRANT, a citizen of the United States, and a resident of San Jose, in the county of Santa Clara and State of California, have invented certain new and useful Improvements in Smoking Devices, of which the following is a specification.

The present invention relates to that class of smoking devices wherein the smoke of the burning tobacco is passed through a liquid in its journey to the smoker's mouth.

It is one object of the invention to provide a device of the character indicated in which a common drinking glass or similar receptacle is used as the liquid containing part of the device.

It is another object of the invention to provide a device of the character indicated so formed and constructed as to permit certain essential portions thereof to be readily packed into small compass to permit carrying in a purse or bag, and quickly mountable on a glass or similar receptacle when desired for use.

It is still another object of the invention to provide a device of the character indicated that may be removably mounted on a glass or similar receptacle in such a manner as to secure an airtight joint between the two.

Finally, it is an object to provide a device of the character indicated that is simple in form and construction, economical to manufacture, quickly and easily mountable in position on a receptacle or removable therefrom, and highly efficient in its practical application.

In the drawing:—

Figure 1 is a plan view of the device, a portion of the smoking tube being broken away.

Figure 2 is a section on line 2—2 Figure 1.

Figure 3 is a detail section through a portion of the device showing another embodiment of the invention.

Referring more particularly to the drawing, 1 is an annular disc provided with oppositely extending flanges 2 and 3 on its outer edge. The diameter of this disc 1 is in the present case slightly less than the diameter of the upper edge of the receptacle 4 on which it is to be placed.

At 5 I show a band of elastic material such as rubber securely mounted upon the pe-

riphery of disc 1 and extending a distance 55 below the flange 3.

By means of this construction the band 5 may be quickly turned up into the position shown in dotted lines at 6 and the disc 1 removed from receptacle 4. Likewise, the 60 disc 1 may be placed in position on receptacle 4 and the elastic band turned down over its upper edge as shown, thereby securely holding the disc in position thereon and providing an airtight joint therebetween. 65

At 7 I show an upstanding annular flange on disc 1 arranged in axial alignment therewith and providing a socket 8 in which a cigarette as 9 may be placed.

At 10 is shown a depending annular flange 70 on disc 1 arranged in axial alignment therewith and providing a socket 11 in which a tube 12 is secured. A conduit 13 connects the base of socket 8 with the base of socket 11. 75

An orifice 14 is provided in disc 1 through which is inserted one end of a smoking tube 15, the other end of the tube being provided with a mouth-piece 16.

When disc 1 and the parts carried thereby 80 is mounted on a receptacle 4 as described, with a quantity of water in the said receptacle as indicated at 17, it is ready for use. A cigarette 9 being set in socket 8 and lighted, the air in the upper portion of the 85 receptacle 4 is partially exhausted by the smoker through the use of tube 15. Since the joint between the disc 1 and receptacle 4 is air tight the reduction of air pressure in receptacle 4 results in air and smoke being drawn through the cigarette, tube 12 and water 17 to tube 15 and thence to the mouth of the smoker. 90

It is obvious, of course, that the disc 1 may be made in many shapes and may be 95 adapted for use with tobacco in different forms and receptacles of different sizes and kinds. It is also clear that other means may be provided for mounting the disc upon the receptacle. It is, therefore, to be understood 100 that while I have herein shown and described but one specific embodiment of the invention, changes in form, construction and method of operation may be made within the scope of the appended claims. 105

The flange 2 fills a twofold purpose. It not only increases the width of the perimeter of the disc 1 whereby to form a satisfactory

foundation for the band 5, but it also forms in conjunction with the flange 7 and body of disc 1, an ash tray 18. This tray completely encompasses the flange 7 and socket 8 so as 5 to catch all ashes falling from the tobacco burning in the said socket 8.

In the partial detail section in Figure 3 it is shown that the band 5 may have a bead formed on one edge as at 19 fitting 10 into a groove 20 in the outer perimeter of disc 1. By this method of construction the band may be readily removed and replaced with a new one if so desired.

I claim:—

15 1. A device of the character described comprising a disc, a resilient annular band carried thereby and adapted to overlap and

engage the receptacle upon which the disc is placed to form an airtight joint therebetween, and tobacco holding means and smoke 20 conduits carried by said disc.

2. A device of the character described comprising a disc having an annular upturned flange on its outer edge to form a relatively wide perimetrical surface and a 25 dished top surface on said disc, a resilient annular band mounted upon said perimetrical surface and adapted to overlap and engage the receptacle upon which the disc is mounted to form an airtight joint therebetween, and tobacco holding means and smoke 30 conduits carried by said disc.

ALEXANDER D. GRANT.
